CARTRIDGE FUSE

Oscar H. Jung and Paul E. Heffelfinger, Milwaukee, Wis., assignors to Trico Fuse Manufacturing Co., Milwaukee, Wis., a corporation of Wisconsin

Application October 29, 1934, Serial No. 750,499

4 Claims. (Cl. 200—131)

This invention relates to electric fuses, and more particularly to that type commonly known as a renewable knife blade cartridge type.

Fuses of the foregoing character are so constructed that the terminals are readily removable from the casing, to permit renewal of the fuse link and facilitate cleaning of the casing after the fuse is blown. To accomplish this, it is customary to lock one of the terminals against longitudinal movement, with the result that upon blowing of the fuse the opposite terminal is free to move into the casing and cause possible arcing and undesired closing of the circuit. Also, when only one of the terminals is anchored, considerable strain is placed upon the soft renewal link, frequently causing the same to warp and sag.

To overcome the foregoing objections, numerous attempts have been made to lock both terminals against longitudinal movement, as well as against rotation, but these have been costly, complicated, and awkward. It is therefore the primary object of the present invention to provide an exceedingly simple and inexpensive fuse, which can be quickly and easily renewed, and in which the terminal inserted through the casing is securely locked against longitudinal movement.

Incidental to the foregoing, a more specific object of the present invention is to provide resilient means for clamping engagement with one of the fuse link terminals, said means being operatively effected upon actuation of a cap connected with the end of the casing.

A still further object resides in the provision of a split resilient ring adapted to be forced into binding engagement with the edge or edges of one of the terminal knife blades upon actuation of a cap associated with the terminal receiving member.

With the above and other objects in view, which will appear as the description proceeds, the invention resides in the novel construction, combination, and arrangement of parts, substantially as hereinafter described and more particularly defined by the appended claims, it being understood that such changes in the precise embodiment of the herein disclosed invention may be made as come within the scope of the claims.

In the accompanying drawing is illustrated one complete example of the physical embodiment of the present invention constructed according to the best mode so far devised for the practical application of the principles thereof.

In the drawing:—

Figure 1 is an elevation of a renewable knife

blade cartridge fuse, partly broken away and in section to more clearly illustrate structural details.

Figure 2 is an end elevation, partly in section.

Figures 3 and 4 are fragmentary elevations of a modified form of the invention, parts being broken away and in section.

For illustrative purposes only, a more or less conventional structure of fuse has been shown. However, it is to be understood that the invention, which resides primarily in the provision of novel means for locking the knife blade terminal against longitudinal movement, may be applied to various structures of cartridge fuses, without departing from the principles thereof, and therefore the invention is not to be limited in any way to the structure of the terminal, or terminal receiving member.

In that type of fuse disclosed, the numeral 1 designates a cylindrical casing, usually formed of fibre, and having its end internally threaded at 2, for the reception of a shouldered sleeve 3, the exposed shoulder portion being externally threaded to receive an end cap 4. Seated upon the end of the sleeve 3, and held against rotation thereon in any suitable manner, is a slotted disc 5, which receives the knife blade terminal 6 to hold the same in alignment with the opposite terminal. The usual fusible link 7 is detachably connected to the inner end of the terminal blade 6 by a bolt 8, or other conventional form of attachment, and rigidly mounted on the shank of the blade 6 is a washer 9, which abuts the inner face of the slotted disc 5 to limit projection of the blade through the disc, and also to effectively close or obstruct the opening between the slot in the disc 5 and the blade.

In conventional fuse structures the slotted disc is locked upon the sleeve 3 by the threaded cap 4, the inturned annular flange 4' being of sufficient diameter to clear the blade and engage the outer face of the disc 5 adjacent its periphery. On the other hand, a closure for the end of the fuse can be effected by forming the slotted end integral with the sleeve 3. However, this is not as desirable as the structure illustrated, in that the sleeves 3 are usually permanently connected to the ends of the casing by rivets, or other forms of permanent attachment, and, therefore, difficulty is encountered in effectually cleaning the interior of the casing after the fuse is blown.

As best shown in Figure 1, the inner periphery of the flange 4' is conically formed to provide an annular tapered face 10, which engages a resilient split ring 11 positioned against the outer face of

the slotted disc 5. Due to the resiliency of the ring 11, the same is normally expanded to permit the blade 6 to be projected through the slotted disc 5 and the end cap 4. However, as the cap 4 is turned down upon the shouldered threaded portion of the sleeve 3, the tapered face, engaging the ring 11, causes the same to be retracted and forced into binding engagement with the edges of the blade 6, thus effectively locking the blade 10 against longitudinal movement. While it is not essential to lock the split ring 11 against rotation, should this be desired one end of the ring 15 may be turned downwardly at 11' for engagement in a recess 5' formed in the disc 5 adjacent its outer periphery. Obviously, rotation of the cap 4 will then have no turning effect upon the ring 11, eliminating a possibility of the split ends 20 of the ring straddling one edge of the blade 6, which may otherwise occur.

Referring now more particularly to that form of the invention disclosed in Figures 3 and 4, the locking operation is reversed, in that the split resilient ring 11 is seated upon a tapered 25 annular face 12 formed internally at the end of the sleeve 3'. In this instance, the blade 6 has rigidly secured thereto a conical washer 13, instead of the flat washer 9 heretofore described, and in operation, as the cap 14 is turned down 30 on the sleeve 3', the slotted disc 5, engaging the ring 11, forces the same downwardly on the tapered face 12, causing the ring to be retracted and forced into binding engagement with the conical washer 13.

As best shown in Figure 3, the ring 11 is normally expanded so as to permit the blade 6 to pass through the same during assembly of the fuse. Then, as the cap 14 is turned down to lock the slotted disc 5 on the end of the sleeve 3', the ring 35 is retracted, as shown in Figure 4. The advantage of this structure resides in the fact that the conical washer serves to center the terminal with relation to the casing, and inasmuch as the split ring 11 is forced into binding engagement with the washer throughout substantially its entire periphery the terminal is securely and firmly held against lateral tilting in any direction.

From the foregoing explanation, considered in connection with the accompanying drawing, it 50 will be readily seen that an exceedingly simple, inexpensive, and effective method has been devised for locking the terminal of a knife blade renewable fuse against longitudinal movement, and inasmuch as the point of engagement between the terminal and the resilient clamping member may vary, shrinkage or expansion of the casing 1 will have no effect upon the locking of the terminal.

Also, particular attention is directed to the fact that it is in no way necessary to alter the structure of conventional fuses, in order to apply the present invention, other than to provide a tapered, annular face upon one of the terminal receiving members for camming and forcing the

split ring into binding engagement with the terminal. In renewing the link or cleaning the casing, slight turning of the caps 4 or 14 quickly relieves the bind on the terminals, and permits the same to be readily withdrawn and again inserted. For the purpose of economy, the split ring 11 is preferably formed from round spring wire. However, it is to be understood that various types and structures of resilient clamping members may be employed, and also while it is 10 preferred to grip the opposite edges of the knife blade, the clamping member may be so designed as to engage only one edge of the blade.

In equipping the fuse with the present invention, no additional mechanical operations are required, it being merely necessary to snap or insert the split ring into position between the retaining elements.

We claim:—

1. A renewable knife blade cartridge fuse comprising a casing, a renewable fuse element including knife blade terminals, terminal receiving members carried by the ends of the casing, resilient means associated with one of said terminal receiving members for binding engagement with at least one edge of the terminal received thereby, and means carried by said member for forcing said resilient means into engagement with the terminal.

2. A renewable knife blade cartridge fuse comprising a casing, a renewable fuse element including knife blade terminals, terminal receiving members carried by the ends of the casing, a resilient split ring associated with one of said terminal receiving members for binding engagement with the edges of the terminal received thereby, and means carried by said member for forcing said ring into engagement with the terminal.

3. A renewable knife blade cartridge fuse comprising a casing, a renewable fuse element including knife blade terminals, terminal receiving members carried by the ends of the casing, a resilient split positioned against the outer face of one of said terminal receiving members, and a rotatable cap connected with said terminal receiving member for camming the split ring into binding engagement with the edges of the terminal.

4. A renewable knife blade cartridge fuse comprising a casing, a renewable fuse element including knife blade terminals, terminal-receiving members carried by the ends of the casing, a resilient split ring associated with one of said terminal-receiving members for binding engagement with at least one edge of the terminal received thereby, said ring having interengagement with the terminal-receiving member to prevent relative movement, and means carried by said terminal-receiving member for forcing the said ring into engagement with the edge of the terminal.
